W. H. BAER.
MAN'S GARTER.
APPLICATION FILED JULY 23, 1921.

1,434,729.

Patented Nov. 7, 1922.

UNITED STATES PATENT OFFICE.

WILLIAM H. BAER, OF PORTLAND, CONNECTICUT, ASSIGNOR TO THE RUSSELL MFG. CO., OF MIDDLETOWN, CONNECTICUT, A CORPORATION.

MAN'S GARTER.

Application filed July 23, 1921. Serial No. 486,965.

To all whom it may concern:

Be it known that I, WILLIAM H. BAER, a citizen of the United States, residing at Portland, in the county of Middlesex and State of Connecticut, have invented a new and useful Improvement in Men's Garters; and I do hereby declare the following, when taken in connection with the accompanying drawings and the characters of reference marked thereon, to be a full, clear, and exact description of the same, and which said drawings constitute part of this application, and represent in—

Fig. 1 a view of a garter constructed in accordance with my invention, as it appears when laid flat or extended its full length.

Fig. 2 a perspective view of the garter as applied to the right leg.

Fig. 3 a perspective view of the garter as applied to the left leg.

Fig. 4 an enlarged broken view of the garter in vertical section, showing the swiveling of the suspension-member of the stocking-gripping device.

25 My invention relates to an improvement in men's garters of the type in which a stocking-gripping device is suspended from a band passing around the leg, the object being to produce a simple and convenient garter of the type described which automatically adjusts itself for use on either leg.

With these ends in view, my invention consists in a men's garter having certain details of construction as will be hereinafter described and pointed out in the claim.

In carrying out my invention, as herein shown, I mount the metal suspension-member 5 of the stocking-gripping device, whatever the character of the same may be, so 40 that it will freely swivel upon the stud 6 provided for being engaged by the fastening-loop 7 connected with the outer end of the leg-band 8, also furnished at its said outer end with a slide-buckle 9 for adjusting 45 its length.

As shown, the stud 6 is mounted in a sheet-metal stud-carrier 10 secured by stitching 11 to the middle of the outer face of a triangular reinforce or pad 12 applied to the 50 outer face of the inner end of the leg-band 8, the inner face of the band having a corresponding pad 13. The lower end of the stud-carrier 10 is upset, as at 14, to receive the rivet-head 15 produced upon the inner

end of the stud 6, which is formed with a 55 step 16 wide enough not only for the reception of the swiveled suspension-member 5 but also for the reception of a washer 17, which positions the suspension-member upon the stud without, however, preventing 60 it from swiveling freely between the washer and the stud-carrier. Specifically, the washer prevents the suspension-member 5 from riding forward upon the stud and interfering with the convenient application of the fastening-loop 7 thereto.

The stud 6 is also formed with a step 18 larger in diameter than the step 16 and formed with a head 19, the step 18 being provided for the reception of the fastening-loop 7, which is retained in place upon the stud by the overhanging head 19 thereof.

As shown, the stocking-gripping device consists of a button 20 mounted upon a plate 21 having slots through which a narrow 75 band 22 of fabric is passed, the upper portion of this band being also passed through a slot 23 in the lower end of the suspension-member 5 and being formed with a loop 24 for the support of a wire gripping-loop 25, 80 which coacts in the familiar manner with the button 20.

But whatever the specific character of the stocking-gripping device, it will be free to swing in either direction with the swiveled 85 suspension-member 5 upon the stud 6, so as to automatically convert the garter for use on the right or left leg, this being entirely a question of the position of the stocking-gripping device when the garter is applied 90 to the leg.

My improved garter is used in the ordinary manner of such garters, the stocking-gripper falling into place whether the garter is applied to the right leg or to the left 95 leg, and the fastening-loop being engaged with the stud from which the stocking-gripping device is suspended without interfering with the swiveling of the suspension-member thereof.

I do not limit myself to the exact construction shown and described, since, obviously, the details may be changed as well as the type of stocking-gripping device used.

I claim:

100 A men's garter having a leg-band, a fastening-loop applied to the outer end thereof, a pad located at the inner end thereof,

- a stud-carrier applied to the outer face of the said pad by which it is isolated from the leg of the wearer, a stud mounted in the said carrier and formed with two steps, of 5 which the inner is smaller in diameter than the outer, and with a head at the outer end of the larger of the said steps, a suspension-member swiveled upon the inner step of the stud, and a positioning-washer interposed 10 between the outer face of the said suspension-member and the inner end of the larger

outer step of the stud, whereby the larger step of the stud is left free for the removable engagement with it of the fastening-loop at the outer end of the leg-band.

In testimony whereof, I have signed this specification in the presence of two subscribing witnesses.

WILLIAM H. BAER.
